SEALED RECEPTACLE

Edward H. Fabrice, Chicago, Ill., assignor to
 Guardian Safety Seal Company, Chicago, Ill.,
 a corporation of Illinois

Application March 31, 1937, Serial No. 133,957

1 Claim. (Cl. 215—46)

This invention has for its main object to provide so-called tamper-proof sealed receptacles comprising receptacles and sealing caps therefor, the latter composed of a resilient sheet metal, such as sheet aluminum, aluminum alloy, or the like, which are required to be severed into two or more parts in order to effect unsealing of the receptacle and which are characterized and distinguished from the prior art in several essential particulars, as follows:

(1) That they are applicable only to receptacles such as bottles, equipped with special formations adapted to cooperate with parts of the caps for preventing unsealing of the receptacle otherwise than by severing the caps into a plurality of parts.

(2) To provide the bottle, or other receptacle, and the sealing cap for the same with preformed cooperating formations which are telescopically engaged with each other as a primary step in the production of a sealed receptacle for preventing rotation of the cap relatively to the receptacle in at least the direction required to effect unsealing of said receptacle.

(3) In providing receptacles equipped adjacent their discharge ends with formations, such as screw-threads or bayonet joint formations, which constitute the equivalent of mandrels utilized as a means for effecting the formations in the cap after the latter is mounted upon the receptacle as aforesaid for cooperation with said last-named formations of the bottle, to prevent relative longitudinal movement of receptacle and cap for unsealing the latter and which, therefore, cooperate with the first-mentioned telescopically interengaged formations to prevent all relative movement between the cap and the receptacle.

(4) In providing the crown portion of the cap with formations which afford a strong digital grip thereon such as will enable a woman or child to effect unsealing of the receptacle without resort to any other operation, the crown portion of the cap being then operable to unseal and reseal the receptacle at will.

(5) To so shape the sealing cap as to the portion thereof cooperating with formations on the bottle neck for preventing relative rotation of the bottle and cap in a direction to unseal the former as will distinguish the cap easily and radically from other bottle sealing caps in a manner tangibly appreciable to touch and eye and, further, to so shape the caps as to render them difficult to reproduce except at great expense for special tools and equipment and thus practi-

cally obviate the refilling of the empty bottles with "bootleg" liquor or other beverage.

The invention may be variously embodied, and in the accompanying drawing several exemplary embodiments thereof are illustrated.

In said drawing,

Fig. 1 is a perspective view showing the cap of this invention in its unfinished state disposed above a neck of a bottle constructed in accordance with the invention.

Fig. 2 is a perspective view of a bottle neck and sealing cap, respectively, constructed in accordance with the invention, the cap being mounted on the bottle to seal the latter.

Fig. 3 is a view similar to Fig. 2 illustrating another or modified embodiment of the invention.

Fig. 4 is a view similar to Fig. 1 showing the cap of Fig. 3 mounted upon the bottle in sealing condition.

Long practice and experience in the art to which the invention relates, has demonstrated that the sealing caps need only to be held against loosening under the combined influences of handling, vibration and variations in temperatures in order to prevent leakage before they reach the consumer. Hence, the connection between the crown portions and base portions of the caps may be so weak and delicate as to permit them to be separated from each other very easily in digitally effecting unsealing of the bottle or other receptacles to which said caps are applied.

Heretofore it has been common practice to provide the sealing caps of the so-called tamper-proof and severable type with annular tear-out strips between their ends which are integral parts of the caps and are bordered by weakening formations such as are illustrated and described in the patents to W. A. Stattmann, Nos. 1,481,034 and 1,481,035. But as these tear-out strips are required to be of appreciable width in order to leave them strong enough to obviate their tearing apart during the removal thereof, they are not well adapted for inclusion in the shorter caps now preferred by the liquor trade to fit shortneck bottles, because, if used in the latter, the thread formations of the bottle and the crown portions of the caps would be shortened appreciably and afford less secure resealing means for the bottle than is afforded by the longer threads. In some instances a very secure resealing is required and in most instances it is preferred and, therefore, the omission of the tear-out or rip-strip above referred to and the substitution of a plurality of spaced apart ar-

cuate severance slits, such as are exemplified in Figs. 1 and 5 of patent to Houghton No. 657,067, have been substituted herein. These arcuate slits are separated from each other by 5 very narrow unbroken parts of the cap which sever easily by merely rotating the crown portion of the cap relatively to the base portion thereof. Both types of cap-severance means above-referred to are old in the art and are interchangeable in practically all types of tamper- 10 proof severable caps without lending to or destroying the novelty of other features of construction.

It is also very desirable that it shall be easily 15 determinable by the consumer whether the bottle was unsealed before being delivered to him and to this end the bottles and caps embodying the present invention are so formed and designed as to render easy the detection by the consumer of 20 the fact that the bottle has been unsealed before delivery to him and, further, it is very desirable that the sealed structure shall present a distinctively different appearance than is common to the general run of sealed bottles in order that 25 the consumer may recognize the genuine nature of the particular brand of liquor or other product which he is accustomed to purchase by the distinctive appearance and tangibly appreciable structural characteristics of the sealing means, 30 and shall not be dependent upon only the labels on the bottles to determine the original of the contents. The latter are too readily and generally reproduced by illicit dealers to render them reliable as a means of identification of origin. 35 Thus, the cooperating sealing means of the bottle and cap of distinctive form and appearance constitutes more or less the equivalent of a trademark of the producer.

Another and unusual object of the present invention is to produce a sealing cap of the type 40 specified which presents difficulties of manufacture so that it cannot be produced cheaply except in large quantities and by means of special and expertly designed equipment costing a great deal, as this constitutes the greatest safeguard 45 against manufacture of the caps in the small quantities required by illicit dealers, usually termed—"bootleggers"—who purchase discarded empty bottles from junk dealers, fill them with 50 cheap product and sell them through illicit channels. It is well known that this illicit trade can obtain labels (duplicating those of original 55 producers) and can also obtain from small shops the necessary lots of caps, such as are illustrated in the above-mentioned Stattmann patents and also in the Fabrice Patent No. 1,771,034, because they are relatively easily produced by ordinary 60 shop equipment and relatively simple dies and tools at a price that the large legitimate producer or bottler would deem prohibitive, but which the bootlegger will pay because the sale of his product is dependent largely upon duplication of the 65 original package as to every detail of its appearance. The secrecy of the bootleggers' operations is extended to the makers of the caps and labels 70 who are as difficult to trace as the average clever criminal.

Therefore, the protection of the public against 75 fraud and deception, as well as protection of the originator of the genuine product, is greatly increased by placing every possible obstacle in the path of the bootlegger in the matter of close imitation of original packages, the greatest obstacle being prohibitive cost of the tamper-proof seal- 75 ing cap.

Another object of the present invention is to provide caps which, while fundamentally alike, may be produced in a large variety of different shapes or designs to fit bottles specially made to receive the respectively different shapes of 5 caps, as this enables each of a number of producers of different brands and types of products to enjoy the exclusive right to purchase and use one of the several different shapes of bottles and caps, the adoption of any one of these being 10 usually dependent upon the enjoyment of an exclusive license by the purchaser.

Hence, the present invention affords a means whereby the use of tamper-proof caps may be vastly increased and the best interests of the 15 consuming public promoted.

In the structure of Figs. 1-3 inclusive, the bottle neck is equipped with interrupted threads 45 at diametrically opposite sides. Below said threaded portion said neck is equipped with an annular rib or collar formations 46 provided with recesses 47 disposed in vertical alignment with the spaces between the thread formations 45.

The cap 48 is of a diameter in its crown portion to snugly fit telescopically over the threads 45 of the neck, the lower end of the cap being annularly slightly enlarged to provide an increased diameter skirt portion 49. The latter is equipped at diametrically opposite points with arcuate removable panel formations 50, each of 30 which is bordered by a U-shaped scoring 51 for weakening the metal. One end of said panel formation 50 is completely severed from the skirt portion 49 by means of a U-shaped incision or slit 52 which borders a digitally engageable 35 tongue 53.

In the body portion of the panel formation 50 there is formed an inwardly projecting box-like formation 54 which fits telescopically into the recess 47 and serves to hold the cap against rotation relatively to the bottle neck.

In the crown portion of the cap 48 at diametrically opposite sides thereof and spaced arcuately from the panel members 50 are two panel formations 55 in which thread formations 56 are 45 formed after the cap is mounted upon the bottle neck and while said cap is held compressed upon the rim of the bottle mouth.

The thread formations 56 of the panels 55 prevent longitudinal movement of the cap relatively to the bottle neck and thus cooperate with the recess 47 and the box-formation 54 to hold the cap rigidly against movement relatively to the bottle until the said panel members 50 are removed or torn out of the structure at both 55 sides of the cap and thereupon the cap may be rotated for removal and replacement.

Obviously in the case of the structure of Figs. 1-3, a single panel member 50 and a single recess 47 will suffice.

As shown in Fig. 4, the box-like formation 54, shown in Fig. 3, may consist of a similar formation 57 of triangular shape in plan view instead of rectangular shape illustrated in Fig. 3, which will likewise prevent rotation of the cap counter-clockwise for effecting its removal from the bottle neck.

While in the several structures shown and described the receptacles are bottles or bottle necks, it will be understood, of course, that the bottle necks illustrated are merely exemplary of receptacles of any kind adapted to be sealed by means of sealing caps constructed in accordance with the invention and which cooperate with cor- 75

responding formations on the receptacles to effect sealing of the latter.

It will be understood, of course, that the several embodiments of the invention herein illustrated and described, are merely exemplary of a substantially infinite number of embodiments thereof differing from each other in appearance but all of which embody the structural characteristics of the structures shown and described.

10 I claim as my invention:

A sealed receptacle comprising a receptacle equipped with an externally threaded mouth portion, the threads of which are interrupted at diametrically opposite points to provide free spaces between the opposed ends of the thread formations, an annular outwardly projecting bead disposed on the bottle neck below the threads thereof and equipped at diametrically opposite points with recesses disposed in alignment with the spaces between the opposed ends of the threads and each of said recesses presenting a side wall constituting a stop formation, a sealing cap mounted on said receptacle and having an annularly enlarged base portion telescopi-

cally receiving the annular bead of the receptacle, a tear-out strip in said enlarged portion of said cap extending arcuately over the recesses in the bead of the receptacle, said strip being equipped at one end with a free digitally engageable tongue and equipped between its ends with an inwardly projecting tongue engaging in said recess with its free end disposed in contact with said side wall of said recess in said bead for preventing rotation of the cap counter-clockwise for effecting removal thereof and thread formations in said cap above said enlarged base portion thereof offset laterally from said tongue of said rip-strip and engaged with thread formations of the receptacle at one side of the space between the opposed ends of said thread formations, the length of the thread formations of the cap being substantially equal to the length of the last-mentioned free space, whereupon by rotating said cap counter-clockwise for a distance substantially equal to the length of the threads therein, said cap may be removed following removal of the rip strip.

EDWARD H. FABRICE.
